AIR CONDITIONING DEVICE

Emert J. Lattner, Cedar Rapids, Iowa

Application April 8, 1935, Serial No. 15,230

4 Claims. (Cl. 261—92)

This invention relates to air conditioning systems and devices and has particular relation to a heat exchange system and to a humidifier and dehumidifier for such a system.

5 It is a general object of my invention to provide an improved and simplified heat exchange mechanism, humidifier and dehumidifier.

An object of my invention is to provide means for circulating an air current and for introducing moisture into and removing moisture from 10 such a current.

Another object of my invention is to provide means for cooling an air current.

Another object of my invention is to provide 15 a plurality of surfaces located in the air stream and means for constantly moistening these surfaces as the moisture is removed therefrom by the circulating air current.

Another object of my invention is to provide 20 an extremely simple drive for moving moistened surfaces into the air current.

Another object of my invention is to provide, 25 in a humidifier employing movable moistened surfaces, an extremely simple means for producing air circulation through the humidifier, and for moistening the surfaces and moving them into the air current.

Another object of my invention is to provide 30 means for removing dust and any form of particles from the air current.

Another object of my invention is to provide 35 an air conditioning device in which the air passing through the machine is not discharged in a cold intense blast but issues therefrom in a widely dispersed stream.

Another object of my invention is to provide for direct recirculation through the humidifier of part of the air issuing from the humidifier.

Other and further features and objects of my 40 invention will be more apparent to those skilled in the art upon a consideration of the accompanying drawings and following specification, wherein is disclosed several exemplary embodiments of the invention, with the understanding, 45 however, that such changes may be made therein as fall within the scope of the appended claims without departing from the spirit of the invention.

In said drawings:

50 Figure 1 is a view, partly in section and partly in elevation, of a device constructed according to one embodiment of my invention.

Figure 2 is a view, partly in elevation and partly 55 in section, illustrating a novel form of hot air furnace and how an air conditioner, a humidifier

and dehumidifier, constructed according to another embodiment of my invention, may be incorporated in such a furnace; and

Figure 3 is a view, in section, of the air conditioning device shown in Figure 2 and taken 5 along the line 3—3 of Figure 2.

Referring now to the drawings and more particularly to Figure 1, there is shown at 10, generally, a humidifier frame or casing including legs or uprights 11, one at each of four corners, rails 12 near the bottom of the uprights for connecting them, rails 13 at the upper ends of the uprights for connecting the upper ends, and a cover 14 for covering the frame.

Perforated panels 16 are inset in the side and 15 end walls and the openings 17 through these panels are of sufficient diameter to permit air to flow into and out of the humidifier without materially retarding the air flow. Filter screens 15 of cloth or the like are usually provided 20 inside the panels 16. Supporting rails 18 are provided on the inside of the walls of the humidifier and these horizontally extending supporting rails are secured at their ends to the 25 legs 11.

A rectangular plate 19 is provided which is adapted to be horizontally disposed within the humidifier to divide the interior thereof into two chambers 33 and 34. The dimensions of this plate are such that it fits closely against the walls 30 of the humidifier frame and rests on the supporting rails 18. The central portion of the plate 19 is upstruck to provide a circular flange 19a and thus forms a cylindrical opening 21 through the plate for permitting a flow of air from the upper 35 chamber 33 to the lower chamber 34, as herein-after more particularly explained.

A U-shaped motor-and-disc-support bracket 22 is secured in an inverted or depending position below the plate 19 as by means of bolts 23. A 40 horizontally extending portion 22a of the bracket 22 extends from side to side across the opening 21 and a central portion 22b is cranked upwardly to provide a recess in which a motor 24 and reduction gear 24a may be mounted. Depending arms 45 22c and 22d are provided on either end of the bracket 22 and these arms are inclined outwardly for a purpose hereinafter more particularly described. The arms 22c and 22d terminate in bosses 22e and 22f. A pair of inwardly and downwardly inclined rods or stub shafts 26 and 27 are received in the bosses 22e and 22f. These rods are placed at right angles to the arms 22c and 22d.

A rectangular pan 28 is disposed in the lower 50

portion of the humidifier and almost completely fills the lower portion of the inside thereof. The pan 28 is secured to the legs 11 by means of small brackets 29. This pan may be filled with water 5 and, if desired, water may be fed into the pan through a float controlled valve 25 (Figure 3). The pan may be drained by the drain valve 30 and if the level of water in the pan becomes too high the excess may be discharged through an 10 overflow pipe 35.

A fan 31 is mounted on the vertically extending shaft 32 of the motor 24, and the motor and fan are so located that the fan rotates in a horizontal plane within the cylindrical portion 19a 15 of the plate 19 and thus draws air into the openings 17 of the upper portion of the panel 16 and through the filter cloth 15 into the chamber 33 down through the opening 21 in the center portion of the plate 19, into the chamber 34, between 20 and over the moistened discs 36 to pick up moisture from the discs, and out through the screen 15 and panel 16 at the lower portion thereof. The direction of movement of the air is indicated by the arrows on the drawings. It is to 25 be noted at this point that the panels 16 are on all four sides of the humidifier and that in this manner air is drawn into the humidifier from four sides so that there is not any great rush of air at any one point. This same condition exists 30 on discharge of the air, since the discharge is also on all four sides of the humidifier, and in fact some of the air discharges from the lower part of the humidifier, passes into the air being drawn into the humidifier and is recirculated. 35 This recirculation of air is of advantage since it permits a two step humidification of the air, and inasmuch as the air may not be completely humidified on first passing through the humidifier, its moisture content may be increased before 40 it is finally discharged from the humidifier.

The mechanism for introducing moisture into the stream of air includes a plurality of discs 36 spaced apart on sleeves 37 and 38. The discs 36 are preferably of wire mesh and this wire mesh 45 is usually of non-corrosive material. Spoked end discs 39 are provided on the outer ends of the sleeves 27 and 28 nearest the bosses 22e and 22f, and another set of spoked discs 41 and 42 are provided on the inner ends of the sleeves 37 and 50 38. The motor 24 is provided with any suitable form of reduction gearing, which gearing is housed in the casing 24a, and this reduction gearing drives a small shaft 43 on which a small drive wheel or drive pulley 44 is located. The 55 groove of the pulley 44 is filled with a leather or rubber material and the discs 41 and 42 are provided with beveled edge portions 41a and 42a which engage and roll on the rubber filler of the drive pulley 44. The stub shafts 26 and 27 60 are sloped inwardly and downwardly in order that the weight of the discs and end plates will cause the disc assemblies to tend to slide inwardly to thus maintain suitable friction drive engagement between the drive pulley 44 and the discs 41 and 42. The stub shafts 26 and 27 are 65 engaged in the respective bosses 22e and 22f by means of set screws 46 and the entire assembly of discs and stub shafts may be readily removed by disengaging the set screws 46 and pulling the 70 stub shafts out of the corresponding bosses.

An ozonizer 47 may be provided, and this ozonizer is preferably located on the inside of the humidifier just below the top 14 and in one corner of the humidifier plane. The ozonizer may be electrically energized by the same electric cir-

cuit which energizes and controls the motor 24 or may be independently energized and controlled.

The device shown in Figure 1 and just described is particularly suitable for a portable 5 humidifier but, obviously, the humidifier may be employed in stationary machines as well.

In Figures 2 and 3 I have illustrated a novel hot air furnace. A humidifier, constructed according to another embodiment of my invention, 10 may be applied to the hot air furnace. I have also disclosed a novel air conditioning means including a means whereby a relatively large body of cooling water may be employed for cooling the air stream passing through the humidifier and also whereby the body of cooling water may be cooled over long periods of time 15 and stored. The cooling water so stored may be utilized to quickly remove heat from the air stream passing through the air conditioning apparatus even at "peak" conditions where the air temperature is relatively high. In other words I provide means whereby large bodies of cooling water may be cooled by a refrigerator system, the capacity of which system is much less than the 20 capacity necessary to cool air passing through the humidifier at high temperatures or "peak" conditions. The refrigerator unit employed to cool the cooling water may be operated over a long period of time during the time when the 25 air temperature is low, as at night and the cooling water thus stored used during the day when the air temperature is high.

A novel hot air furnace suitable for use with my air conditioning system is indicated generally at 51 in Figures 2 and 3. A base 52 is employed for supporting the front end of the body portion of the heater 53 and the rear end of the heater is supported by a pipe standard 54. The upper portion of the base 52 and the lower front 35 portion of the heater 53 are lined with refractory material 56 to form a fire box 57, and an oil burner 58 or other means for burning fuel is located at the front of the heater, with the blast tube 59 thereof projecting into the heater. The rearwardly extending portion 61 of the heater is provided with a plurality of relatively large vertically-extending pipes 62a, 62b and 62c to provide vertical channels leading through the heating chamber of the furnace to permit the circulated air to be heated. The entire heater is enclosed by a rectangular jacket 63, and air, as indicated by the arrows, may flow in at the bottom of the heater and up through the tubes 62a, 62b and 62c or through the space around the heater 55 between the heater and the jacket 63, and may then pass upwardly through the discharge opening 64. The heated products of combustion, as indicated by the dot-and-dash arrows, may pass upwardly and rearwardly around the first row of tubes 62a, down beneath a transverse vertical baffle 66, around the next row of tubes 62b, over a baffle 66b around the next row of tubes 62c, back down under a baffle 66c and through the stack 67.

The discs 68 of a humidifier, constructed according to a modified form of my invention, are mounted for rotation in the casing 69 at the rear of the heater and are adapted to be driven by a motor 71 in the same manner as they are driven 70 in the device shown in Figure 1. The water for wetting the discs is carried in the pan 72. Air entering through the intake pipe 73 is directed over and between the discs 68 by a deflector 75 and then passes through the filters 74. The air, 75

which is now laden with moisture, is drawn down through the channel 76 by means of a fan 77, which is driven by motor 78, and is driven through the conduit 79 and into the chamber 81 below the tubes 62a, 62b and 62c, where the air then passes upwardly through the pipes and is discharged through the opening 64.

It is to be observed that in this embodiment of the invention, the air circulating means and disc rotating means are driven by separate motors and that the humidifying means is located above the air circulating means in reversed position from that shown in Figure 1. One of the advantages of such a positioning of the humidifier is that a large storage tank 82 may be employed and since the humidifier is located well above the floor level a deep tank of high storage capacity may be employed. In this embodiment of the invention, I prefer to place cooling coils 83 in the storage tank and to employ a refrigerator unit 84 to cool a refrigerant and drive it through the cooling coils to thus cool the cooling water in the storage tank. Water may pass from the storage tank into the pan 72 through the conduit 86 and back into the storage tank through the conduit 87. The well-known thermo-siphon effect may be employed to circulate the water from the storage tank to the wet disc tank 72 and back, or a motor (not shown) may be employed to drive a pump (not shown) for the purpose. It is apparent that the refrigerator unit may run twenty-four hours a day if necessary, in order to cool the entire body of water, so that a large supply of cooled fluid is available during the day when the air temperature is high and the cooling effect is most desirable.

Modifications may be made by those skilled in the art and such modifications may be made without departing from the spirit and scope of my invention as set forth in the appended claims.

I claim as my invention:

1. In a humidifier, a motor, a drive pulley driven by the motor, a stub shaft inclined downwardly in the direction of the drive pulley, and a plurality of discs including a drive disc rotatably mounted on the stub shaft and so disposed that the periphery of at least one of the discs engages the drive pulley whereby the downward slope of the stub shaft causes the drive disc to frictionally engage the drive pulley through the effect of gravity. 5

2. In a humidifier, a drive motor, a drive pulley driven by the drive motor, a plurality of discs rotatably mounted within the humidifier, the axis of rotation of the discs being inclined downwardly in the direction of the drive pulley so that the edge of at least one of the discs is caused to engage the drive pulley and whereby the action of gravity causes the disc to frictionally engage the drive pulley at all times. 15 20

3. In a humidifier, a plurality of rotatably mounted discs, means for mounting the discs for rotation, the axis of which mounting means is disposed at an angle with respect to the horizontal whereby the discs tend to slide downwardly along the axis of the mounting means, a motor and fan for circulating air through the humidifier and pulley means driven by the motor disposed in the path of the discs as they tend to slide downwardly to afford a frictional drive with 25 30 the discs.

4. In a humidifier, a casing, a horizontally extending partition in the casing having an opening therethrough, a bracket depending from the partition, a motor on the bracket, discs 35 rotatably mounted in the bracket, a fan located in the opening in the casing driven by the motor and means for driving the discs from the fan motor. 35
